(57) **CLAIM**

The ornamental design for an enclosed hopper, as shown and described in the attached drawings.

DESCRIPTION

FIG. 1 is a front view of enclosed hopper showing my new design.

FIG. 2 is a left side view thereof; and,

FIG. 3 is a top view thereof.

Grain elevator and Grain Bin are shown in broken lines as they form no part of enclosed hopper design.

1 Claim, 3 Drawing SheetsFIG. 1

FIG. 2
